TYPEWRITING MACHINE

Filed Sept. 3, 1927

Fig. 1.

Patented Oct. 9, 1928.

1,687,026

UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed September 3, 1927. Serial No. 217,322.

This invention relates generally to counterbalancing springs for platen-shift typewriting machines, and more particularly to devices for fastening such springs in operative 5 position on a typewriting machine.

In an Underwood typewriting machine, to reduce the effort for operating the usual shift-key, a counterbalancing tensile spring having both ends formed with a bend or hook is provided, and has its front end hooked around a depending bracket fast on the frame of the machine and its rear end hooked on a depending element of a bell-crank, which is swung upwardly for shifting the platen-frame to upper-case position 15 upon operation of the shift-key.

In most cases, the present arrangement of the above-mentioned counterbalancing spring is entirely satisfactory. It has been found, 20 however, that in some offices and in some business schools persons using an Underwood typewriting machine occasionally will carelessly or from ulterior motives displace from operative position or even entirely re- 25 move the usual counterbalancing spring.

It is an object of the present invention to provide devices for securing the platen-shift counterbalancing spring on an Underwood typewriting machine so that it cannot be 30 easily removed therefrom or made inoperative.

In carrying out my invention, the counterbalancing spring has both ends arranged with integral closed rings, and a notched 35 plate is fastened on the usual depending bracket, to which is fastened the forward end of the counterbalancing spring so that a virtual eye or hole is built up for securing the front end of the spring in place. The rear end of the spring is adjustably fastened to the usual notched bell-crank by 40 means of a link having its rear end provided with a tooth for engaging the teeth of the notched bell-crank member. The front end 45 of the link is arranged with a collar held in place by an upset screw, around which collar the rear end of the spring engages.

Other features and advantages will hereinafter appear.

50 In the accompanying drawings,

Figure 1 is a fragmentary view of an Underwood typewriting machine, having my invention applied thereto.

Figure 2 is a bottom view, broken away in 55 part, of the counterbalancing spring and the

devices of the present invention for fastening it to the typewriting machine.

Figure 3 is a disassembled perspective view, partly broken away, of the counterbalancing spring of the present invention, 60 the usual bracket to which the front end of the spring is attached, and the devices of the present invention for securing the spring to the bracket and to the bell-crank, the latter not being shown in this view. 65

In an Underwood typewriting machine, types 10 strike against a platen 11 on a shaft 12 journaled in the sides of a platen-frame 13, which may be swung for case-shift movement on a carriage 14 by instrumentalities 70 including two arms 15, one at each end of the platen-frame. The rear ends of the arms may be fast on a rock-shaft 16, and the front ends engage gudgeons 17 fixed on the sides of the platen-frame. The platen 11 may be 75 raised to upper-case position by operation of the usual shift-key, not shown, which swings a shift-key lever 18 against a downwardly-dependent arm 19 of a bell-crank 20, which is fulcrumed on a lateral rock-shaft 21 and 80 has forwardly-extending arms 22, which support a lateral shift-rail 23 on which runs a roller 24 revolubly mounted on a bracket 25 which supports the platen-frame 13. 85

To reduce the effort required for operating the shift-key in an Underwood typewriting machine, it is usual to provide a lift-rail or counterbalancing spring to help swing the bell-crank 20 upwardly. Such a spring is shown in the patent to William F. Helmond, 90 No. 1,066,275, dated July 1, 1913. Its forward end is usually formed with a bend or hook which engages in a notch 27 of a depending bracket 29 which is fastened by screws 30 to a convenient portion of a main 95 frame 31 of the typewriting machine. The rear end of the lift-rail spring is usually formed substantially like the forward end for engaging in any desired notch between a plurality of teeth 32 provided in a rear upright portion of a usual connecting piece or bracket 33, extending between the outer ends of the arms 19 and 22. 100

While the construction of the lift-rail spring in the above-mentioned patent to 105 Helmond is generally quite satisfactory, it has been found in certain offices and in business schools that some persons, in using an Underwood typewriter, will accidentally or intentionally displace or remove the usual 110

lift-rail spring connecting an arm 28 of the bracket 29 and the bell-crank 20. To provide means for preventing the easy removal of the kind of lift-rail spring mentioned above, which can be easily attached to a standard Underwood typewriting machine without alteration or change in the latter, a link or clevis 34 has two forwardly-extending side members or arms 35 integrally joined by a rear end piece 36, the arms being spaced apart for engaging loosely around the sides of the bracket 33. A tooth 37, for engaging in the notches between the teeth 32, may be formed by bending an integral lug on the end piece 36 forwardly and downwardly. The forward end of each arm 35 may have a hole 38, the holes being oppositely positioned and one of them tapped for receiving a screw 39, which passes through the other hole and through a small spacing collar 40 to hold it in place between the arms 35. The thickness of the collar slightly exceeds the diameter of the coiled tensile spring 41 whose rear end will terminate in a closed loop 42 large enough in diameter to loosely engage around the collar 40. The forward end of the spring 41 will terminate in a closed loop or ring 43 which engages in the usual forwardly-opening notch 27 in the arm 28. To prevent the removal of the loop 43 from the arm, a substantially T-shaped sheet-metal plate 44 is provided with a rearwardly-opening notch 45 in its upright member 44^a, arranged for loosely fitting over the portion of the loop 43 adjacent the notch 27 when the plate 44 is fastened on the arm 28 by means of a short mounting plate 46 having tapped holes 47 to receive screws 48 passing on each side of the bracket-arm 28 in close proximity thereto through holes 49 in the ends of an upper lateral member 44^b of the T-shaped plate 44. The oppositely-disposed notches 27 and 45 form, in effect, a built-up eye or hole for the loop 43, from which it cannot be removed without first taking out the screws 48, whose removal may be prevented by upsetting the leading ends of the screws 48 after they have passed through the plate 46 (Figure 2). It will be noted that the notch 27, the loop 43, and the notch 45 cooperate to prevent the removal of the plate 44 by slipping it off the bracket 29. The sides of the notch 45, when moved, will be stopped by striking the wire rim of the loop 43 which is held against displacement by engagement with the sides of the notch 27. After the loop 42 has been placed around the collar 40, and the screw 39 threaded through the tapped hole in the arm 35 (Figure 2), the leading end of the screw may be upset to prevent its removal.

It will be noted that the arrangement of the arms 35 and tooth 37 permits the link 34 to have a compact, positive, adjustable engagement with the bell-crank 20, which is

unreleasable by the typist without the use of special tools, which, if employed, would attract immediate attention.

Variations may be resorted to within the scope of the invention, and portions of the improvements may be used without others.

Having thus described my invention, I claim:

1. In a platen-shift typewriting machine, the combination with an upwardly-shiftable bell-crank supporting the platen of said machine, and a bracket disposed forwardly from said bell-crank and having a forwardly-opening notch, of a coiled wire counterbalancing spring for said platen, having each end terminating in a closed ring or loop, the forward loop engaging around said bracket to lie in said notch, a plate disposed against said bracket and having a rearwardly-opening notch registering with said first-named notch, whereby to form a built-up eye whose rim engages around the wire rim of the forward ring of said spring, instrumentalities for fastening said plate to said bracket, and an undetachable built-up link for fastening the rear end of said spring to said bell-crank.

2. In a platen-shift typewriting machine, a built-up link for unreleasably fastening a counterbalancing spring having a closed ring-like end-portion to a platen-shifting instrumentality of said machine, having an upright row of angular notches, said link including side members integrally joined at the rear, one of said members having a plain hole at the front end and the other side member having an oppositely-disposed tapped hole, a screw passing through said plain hole and threaded in said tapped hole and passed therethrough and upset to prevent its withdrawal, a collar around said screw between said side members, and a tooth bent forwardly and inclined downwardly between said side members at the rear thereof for engaging in the notches in said platen-shifting instrumentality.

3. In a platen-shift typewriting machine, in combination, a bell-crank for swinging said platen to upper-case position, having a forwardly-extending arm and a depending arm, and an integral bracket-member connecting the ends of said arms, an upright row of V-shaped teeth in the rear edge of said bracket-member, a counterbalancing spring for said machine, having its rear end terminating in an integral closed ring, means for unreleasably fastening the forward end of said spring to said machine, and instrumentalities for fastening the rear end of said spring to said bracket-member, whereby the spring cannot be removed from said member but may have its pull on said bell-crank adjusted, said instrumentalities including a built-up link having two side members, an integral rear connection for said members, a

connection for the front ends of said side members, including a screw passing through one of said side members and through said closed ring to be threaded through the other 5 of said side members and upset to prevent its removal from said link, a collar around said screw, between said side members, having substantially the same diameter as said closed ring, and an integral tongue on said 10 rear connection extending forwardly between said side members and inclining downwardly for securely engaging in said notches.

4. In a typewriting machine, the combination with a bracket-member having a notch 15 therein, of a coiled wire spring having an end terminating in a closed ring or loop which engages around said bracket to be seated in said notch, and a plate having a notch therein disposed against said bracket 20 so that its notch registers with and is oppositely disposed with respect to the notch in said bracket, whereby to form a built-up eye whose rim engages around the wire rim of said ring, and instrumentalities for un- 25 detachably fastening said plate to said bracket in a manner that disabling of said built-up eye will be prevented.

5. In a typewriting machine, a counter- 30 balancing coiled wire spring with an end terminating in an integral closed ring or loop, a notched bracket-member around which said ring hooks for engaging in the notch thereof, and instrumentalities for building up an eye or hole in said bracket 35 whose rim engages around the wire rim of said loop.

6. In a platen-shift typewriting machine of the class described having mechanism including a bell-crank for raising said platen to upper-case position, in combination, a depending stationary bracket-arm fixed on the frame of said machine disposed in front of said bell-crank and arranged with a forwardly-opening notch adjacent its bottom 45 end, a tensile spring having both ends formed with an integral closed ring or loop, a built-up link for fastening one end of said spring to said bell-crank, including two side members connected at one end by a screw, 50 the latter passing through a closed ring of said spring, and instrumentalities for building up an eye at the notch in said depending arm for engaging around the other ring of said spring, including a plate having a rearwardly-opening notch, and devices for fastening said plate on said downwardly- 55 depending arm.

7. In a platen-shift typewriting machine of the class described having mechanism 60 for raising said platen, the combination

with a counterbalancing spring effective for exerting a raising force on said mechanism, and a stationary bracket on said machine having a forwardly-opening notch in which said spring may be hooked, of means for fastening said spring to said mechanism and to said fixed bracket so as to be secure against easy removal by operatives, said means including a closed ring integrally formed in both end portions of said spring, 65 a built-up link effective for unreleasably fastening one of the rings of said spring to said mechanism, and instrumentalities for building up an eye for said notched member effective for unreleasably engaging the other 70 ring of said spring.

8. In a platen-shift typewriting machine having a coiled wire counterbalancing spring with a closed ring end-element, the combination with a bracket having a notch 80 in a forward edge for receiving said closed ring end of the counterbalancing spring, of instrumentalities for building up an eye for said bracket effective for engaging said ring-element, whereby the latter cannot be easily removed from engagement with said bracket.

9. In a platen-shift typewriting machine having a coiled wire counterbalancing spring with closed ring end-members, the combination with a bracket having a notch 90 in its forward edge for receiving a closed ring end-member of the counterbalancing spring, of instrumentalities for building up an eye for said bracket effective for engaging said ring-member, so that the latter cannot be easily removed from engagement with said bracket, said instrumentalities including a T-shaped plate mounted on a side of said bracket and having an upper lateral member with holes therethrough adjacent each end thereof and spaced for disposition at each edge of said bracket closely there- 100 against when said plate is mounted on said bracket, said T-shaped plate having an up- 105 right member with a rearwardly-opening notch arranged to register with the notch in said bracket to form a hole or eye in said bracket whose rim encloses the wire rim of said ring end-member, a mounting-plate dis- 110 posed on the opposite side of said bracket from said T-shaped plate and having threaded holes disposed opposite the holes in said T-shaped plate, and a screw arranged for passing through each hole in said T-shaped plate to be threaded into the opposite hole in said mounting-plate and to 115 pass through the latter and be upset to prevent its removal.

ALFRED G. F. KUROWSKI.
